UNITED STATES PATENT OFFICE.

HARRY VINCENT BALL, OF MONTREAL, QUEBEC, CANADA, ASSIGNEE TO R. EICH AND CO., OF NEW YORK, N. Y., A CORPORATION OF NEW YORK.

WEB JOINING AND PASTING DEVICE.

Application filed January 26, 1923. Serial No. 614,844.

To all whom it may concern:

Be it known that I, HARRY VINCENT BALL, a citizen of the United States, residing at Montreal, Province of Quebec, and Dominion of Canada, have invented certain new and useful Improvements in Web Joining and Pasting Devices, fully described and represented in the following specification and the accompanying drawings, forming a part of the same.

This invention relates to certain improvements in web joining or pasting devices.

It is the especial object of the present invention to provide an effective construction by means of which the end of the spare or inactive web roll may be secured to the web of a running web roll when the latter is at or near the exhaustion point, the construction being a simple one and one easily manipulated, and which will produce positive and effective joining of the webs.

A further object of the invention is to produce such a construction which may be readily installed in a web machine, as a web printing machine, without changing or redesigning the machine, and which will be simple and inexpensive to make and keep in order.

With these and other objects not specifically referred to, the invention consists in certain novel parts, arrangements and combinations, a detailed description of which will be given in connection with the accompanying drawings, and the novel features thereof pointed out in the claims hereunto annexed.

In these drawings—

Figure 1 is a side elevation, partly broken away, showing the improved pasting device in connection with so much of a web roll machine as is necessary for an understanding of the invention.

Figure 2 is a broken end view of the construction shown in Fig. 1.

Referring now to these drawings which illustrate a preferred embodiment of the invention, the improved pasting device has been illustrated as employed in a construction in which the running and the inactive rolls are carried in fixed bearings, the web in use running from a roll in either one of the bearings. Referring first to the construction shown in full lines in Fig. 1, there is shown an inactive roll 1, mounted in bearings 2, located in lower brackets 3 secured

to the side frames 4 of the machine. Above the lower brackets 3 and at one side thereof, are upper brackets 5 in which are provided bearings 6 for a second roll 7, this second roll being indicated by the full lines as about 60 to expire.

Secured to the lower part of the frames 4 are a pair of brackets 8, having depending legs 9 secured to the floor or other suitable support by bolts 10. These brackets form 65 supports for studs 11, on which are pivotally mounted a pair of frames 12, 13 connected at their upper ends by a cross bar 14. One of these sides frames, as frame 12, is curved, as indicated at 15 so as to extend 70 around and clear the usual roll braking mechanism 16 for the roll in the lower bearings 3. The frames 12, 13 extend below the pivoted point to form supports 17, in which may be secured weights 18 so that normally 75 the frame will swing in an upright position as shown in dotted lines at 19 in Fig. 1, when the device is not in use.

The upper ends of the frame above the cross bar 14, before referred to, is formed 80 with a pair of hubs 20, in which is mounted a shaft 21 extending between the frames and carrying a pasting roll 22. One end of this shaft is provided with a ratchet 23 with which co-operates a pawl 24 pivoted at 25 in 85 the side frame 6, the object of this construction being to prevent the backward rotation of the pasting roll after the web has been secured thereto.

The operation of the device is as follows:— 90 Assuming that the web from the inactive roll 1 in the lower bearings 2 is to be secured to the web of the expiring roll 7 in the upper brackets 5, the operator secures the end of the web W from the inactive roll 1 to the pasting roll 22 by some bond which is easily broken, such as grease put on the roll 22, the pivoted frames being in the position shown in dotted lines in Fig. 1, which in the particular construction shown would give the operator room to do this. If desired, of course, the frames could be swung further to the right in Fig. 1, if additional space was required for convenience in attaching the webs. The frames 100 with the new web attached are then swung to the left as shown in dotted lines, and the end of the new web, to the outer surface of which a suitable adhesive, as paste, has been supplied, will be brought into con- 110

tact with the expiring web from the roll 7 at the desired time, the two webs being squeezed between the roll 22 and co-operating abutment roll 26 over which the running web is led to the printing or other machine and which is secured in the frames 4, before referred to. With this construction the two webs may be brought together with sufficient pressure to ensure an effective pasting and after the paste is made the expiring web may be severed or broken in any suitable manner.

When it is desired to unite an expiring web marked W' from an almost expired roll indicated by the letter E in the lower bearings 2, to the web of a full roll, shown in dotted lines marked 27 in the upper bracket 5, the new roll 27 has paste applied thereto at some point upon its surface. This roll is then rotated in any desired or usual manner and the frame may be swung to cause the expiring web W' to come into contact with the pasted surface of the roll 27. The two webs then pass between the rolls 22 and 26 and the paste made, after which the web W' may be severed or broken as usual.

With this construction a very simple and effective web joining device has been produced, one which can be readily installed in a machine, and is simple and inexpensive to make and easily operated.

While a preferred form of the device has been shown, it will be understood that various changes may be made in the construction of the device and that the invention is not to be restricted to the exact construc-

tion and arrangement of parts shown and described, nor to the arrangement of web rolls shown.

What I claim is:

1. In a web pasting device, the combination of a support for a running roll and for a spare roll, of a swinging frame mounted to swing so as to bring a new web in contact with an expiring web, a pasting roll carried by the frame, and a co-operating abutment for the pasting roll between which and the roll the two webs run and effect a paste.

2. In a web pasting device, the combination of a support for a running roll and for a spare roll, a frame mounted to swing toward and from the web running from either roll, a pasting roll carried by the frame, a co-operating abutment for the pasting roll between which and the roll the two webs run and effect a paste, and means for returning the frame to position after it has been swung to make the paste.

3. In a web pasting device, the combination of a support for a running roll and for a spare roll, a frame including spaced side arms pivoted to swing toward and from the web running from either roll, weights on the arms below their pivot points, a pasting roll carried between the arms above the pivot points and a co-operating abutment roll between which and the pasting roll the two webs pass.

In testimony whereof, I have hereunto set my hand.

HARRY VINCENT BALL.
